Attorney:

UNITED STATES PATENT OFFICE.

JOHN P. WHIPPLE, OF WHITEWATER, WISCONSIN.

PAINT-DISTRIBUTER.

SPECIFICATION forming part of Letters Patent No. 280,696, dated July 3, 1883.

Application filed March 19, 1883. (Model.)

To all whom it may concern:

Be it known that I, JOHN P. WHIPPLE, a citizen of the United States, residing at White-water, in the county of Walworth and State of Wisconsin, have invented certain new and useful Improvements in Paint-Distributers; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 My invention relates to improvements in that class of paint-distributers in which the operative mechanism is driven by a current of air, and the paint is distributed by the joint action of a rapidly-moving reciprocating needle and said current of air, the construction and operation of which classes of paint-distributers are fully illustrated and described in the United States Letters Patent No. 256,852, which were granted on the 25th day of April, 1882.

25 My improvements consist in the peculiar construction of a needle and the device by which it is operated.

Heretofore the paint-distributing needle has been operated by a crank, with which it was 30 connected at its rear end only with the wind-wheel, in which case it became necessary to use a heavy large needle, that the same might have sufficient rigidity to be controlled and operated from its rear end only, and in certain 35 classes of work I have found that it becomes necessary to use a much finer needle for distributing the paint than could be practically used when the needle is thus supported only at its rear end. My invention is further explained by reference to the accompanying 40 drawings, in which—

Figure 1 represents a top view of my improved needle as connected with the operative mechanism. Fig. 2 represents a side view, 45 and Fig. 3 a detail of the same.

Like parts are represented by the similar reference-letters throughout the several views.

A is a wind-wheel, which is adapted to be operated by a current of air conducted thereto 50 by a small tube, as shown in said Letters Patent.

B is a paint-trough, in which a small quantity of paint is placed preparatory to being distributed by the needle.

C is a small tube, through which a current 55 of air is conducted to the needle, which said trough and air-tube are also constructed and adapted to operate substantially as shown and described in said patent.

D is a "paint-distributing needle," so called, 60 which I substitute for the needle heretofore used.

E is a crank, by which motion is communicated from the wind-wheel A to the needle.

Heretofore it has been common to make the 65 needle sufficiently rigid to be supported at its rear end only, in which case none but a large heavy needle could be used. By my improvement the needle is supported at both its front and rear ends by retaining-bow F, by which 70 bow I am enabled to use a very fine, flexible wire, as it is held taut by the bow and prevented from bending or vibrating. The bow F is preferably formed in a single piece, which is attached to the crank E by hinge G, which 75 hinge permits said crank to perform a circular movement as the wind-wheel revolves. The lower arm, H, of the bow operates in a guide-groove, I. The arm H is retained in the groove I by a retaining-button, J. The lower 80 end of the tube C is moved over the places where it is desirous to distribute the paint, while the needle D is caused to reciprocate rapidly beneath said tube. As the needle reciprocates, a small quantity of paint is carried forward 85 with each forward movement of the same beneath the lower end of said tube C. When the current of air escapes from said tube, the paint is blown from said needle and uniformly distributed on the canvas. The needle D is, 90 for the purpose intended, necessarily formed of a slender, delicate wire incapable of sustaining its own weight when supported at one end only. When, however, it is thus attached at its respective ends to the bow F, it is retained in a rigid, taut condition, and is prevented from swaying and bending, whereby 95 much finer and more accurate work may be done than it would be possible to do by the needles as heretofore constructed and operated.

Having thus described my invention, I make no claim herein to the wind-wheel, air-tubes,

paint-trough, or the other parts of the operative mechanism of the machine separately considered; but

What I claim as new, and desire to secure by Letters Patent, is—

1. The combination of paint-trough B, with the distributing-needle D, formed of a slender wire, with a supporting-bow, F, said bow being adapted to support said needle at its respective ends, whereby it is held taut and prevented from bending, substantially as and for the purpose specified.

2. The combination of the needle D, bow F, said bow being adapted to support said needle at its respective ends, crank E, and wind-wheel A, as set forth.

3. The combination of bow F, needle D, as

attached at its respective ends to said bow, crank E, and guide-trough I, substantially as and for the purpose specified.

20

4. The combination of bow F, provided with arm H, needle D, guide-grooves I, crank E, and wind-wheel A, said arm H being adapted to operate in said guide-grooves I, whereby said needle is guided and retained in its proper position beneath the tube C, substantially as and for the purpose specified.

In testimony whereof I affix my signature in presence of two witnesses.

JOHN P. WHIPPLE.
